PUMP.

1,411,793.

Specification of Letters Patent.

Patented Apr. 4, 1922.

Application filed March 31, 1921. Serial No. 457,307.

To all whom it may concern:

Be it known that we, CHARLES E. McGEE and JERRY M. KENT, both citizens of the United States, the former residing at Santa Monica, in the county of Los Angeles and State of California, the latter residing at Los Angeles, in the county of Los Angeles and State of California, have invented a new and useful Pump, of which the following is 10 a specification.

This invention relates to pumps used for pumping various liquids and is particularly related to equipment for pumps used for pumping liquids containing suspended solids 15 of such a nature as to cause the rapid wearing away of the frictional surfaces of the pump.

In pumping liquids containing abrasive substances, the packing used to provide a 20 seal between the piston and the interior walls of the cylinder soon becomes worn to such an extent that the reduced efficiency of the pump necessitates the taking up of the packing, thereby causing a loss of utility 25 during the time consumed in adjusting the packing to overcome this reduced efficiency. Also pumps are allowed to operate at a very 30 low efficiency for long periods of time because of the inconvenience of properly adjusting the packing.

It is the object of this invention to provide a piston which may be quickly adjusted from the exterior of the pump, thereby providing for the practically continuous operation of 35 any pump to which it may be applied. It is also an object of our invention to provide a piston of this type which will be so constructed as to operate in perfect alignment within the cylinder of the pump. Other 40 objects will become evident throughout the following specification.

With reference to the drawing which is for illustrative purposes only:

Fig. 1 is an elevation of a double acting 45 pump having the pumping cylinder in section to illustrate the application of a piston embodying our invention.

Fig. 2 shows the parts comprising the 50 piston shown in Fig. 1 placed in extended disposal.

Fig. 3 is a longitudinal central section of the piston and illustrates the features of assembly thereof.

As shown in the drawing, the piston 11 55 is mounted on a piston rod 12 of a pump

13 and operates within the pumping cylinder 14. The piston 11 comprises essentially a head member 20 and a cap member 21 adapted to slidably enclose the reduced portion 22 of the head 20. When the head 20 is mounted upon a tapered shank 23 of the rod 12, a threaded portion 24 extends beyond the central wall structure 25 of the head 20 and the head is secured upon the shank 23 by lock-nuts 26.

Rings 30 and 31, internally beveled as at 32, fit over the reduced end 22 of the head 20 and enclose the edges of packing 34. The cap member 21 is provided with a hub 35 which is internally threaded at 36, and an operating shank 37 having a reduced and threaded end 38 is screwed into the hub 35 and prevented from turning therein by a taper pin 39. The threaded portion 24 of the rod 12 enters the internal thread 36 of the cap 21 and by turning the shank 37 by means of the squared end 40, which is provided for the application of a wrench thereto, the cap 21 may be screwed forward upon the threaded portion of the connecting rod 70 and any degree of pressure brought to bear 75 upon the packing 34.

In the application of the piston 11 to the pump shown the shank 37 is passed through a stuffing box 50 upon which is 80 screwed a gland nut 51, thereby making it possible to revolve the cap 21 and tighten the packing without the necessity of dismantling the pump, and the pump may 85 thereby be kept working at its highest efficiency.

It will be noticed that the parts of which this piston is composed assemble in such a manner as to provide perfect alignment and in the application of this piston to any pump 90 there will be no danger of scoring the cylinders due to misalignment of the different parts.

This application is in part a division of our application 388,028, filed June 10, 1920. 100

We claim as our invention:

1. In a pump, the combination of: walls forming a cylinder; a cylinder head on either end of said cylinder; a piston rod projecting through one of said cylinder heads 105 into said cylinder; a piston head carried on said piston rod; a cap threaded on said piston rod; packing between said head and said cap; and a shank rigidly secured to said cap and projecting through the other cylin- 110

der head, said shank constructed and arranged for operation to turn said cap on the threaded connection with the piston rod.

2. In a pump, the combination of: walls 5 forming a cylinder; a cylinder head on either end of said cylinder; a piston rod projecting through one of said cylinder heads into said cylinder; a piston head carried on said piston rod; a cap threaded on said piston rod inside said cylinder; packing between said head and said cap; and a shank rigidly secured to said cap and projecting through the other cylinder head, said shank constructed and arranged for operation to turn 10 15 said cap on the threaded connection with the piston rod.

3. In a pump, a piston structure comprising: a piston rod; a head secured axially on said piston rod; a cap threaded on said piston rod; packing between said head and said cap; and means extending outside the cylinder of the pump for turning said cap on said piston rod.

4. In a pump, a piston structure comprising: a piston rod having a threaded end;

a head on said piston rod; means threaded on said threaded end of said piston rod for securing said piston head on said piston rod; a cap threaded on said piston rod outside said means; packing between said head and said cap; and means extending outside the cylinder of the pump for turning said cap on said piston rod. 30

5. In a pump, a piston structure comprising: a piston rod having a threaded end; a 35 head on said piston rod; means threaded on said threaded end of said piston rod for securing said piston head on said piston rod; a cap threaded on said piston rod outside said means; packing between said head and 40 said cap; an operating shank adapted to turn said cap and projecting through the cylinder head of the pump; and packing about said shank where it passes through said cylinder head. 45

In testimony whereof, we have hereunto set our hands at Los Angeles, California, this 25th day of March, 1921.

CHARLES E. McGEE.
JERRY M. KENT.
